UNITED STATES PATENT OFFICE.

JOHN J. McBRIDE, OF NEW YORK, N. Y., ASSIGNOR TO AMERICAN CAR AND FOUNDRY COMPANY, OF NEW YORK, N. Y., A CORPORATION OF NEW JERSEY.

TANK-CAR DOME.

1,370,754.

Specification of Letters Patent.

Patented Mar. 8, 1921.

Application filed August 21, 1919. Serial No. 318,985.

To all whom it may concern:

Be it known that I, JOHN J. McBRIDE, residing at New York, in the county and State of New York, and being a citizen of the 5 United States, have invented certain new and useful Improvements in Tank-Car Domes, of which the following is a full, clear, and exact description, such as will enable others skilled in the art to which it applies 10 to make and to use the same, reference being had to the accompanying drawings, which illustrate the preferred form of the invention, though it is to be understood that the invention is not limited to the exact 15 details of construction shown and described, as it is obvious that various modifications thereof within the scope of the claims will occur to persons skilled in the art.

In said drawings:

20 Figure 1 is a side elevation of a tank car embodying my invention;

Fig. 2 is a vertical section taken on the line II—II of Fig. 1; and

25 Fig. 3 is a vertical section taken on the line III—III of Fig. 1.

With the introduction into commercial use of liquid hydrocarbons obtained by compressing those hydrocarbons found in a normally gaseous state, it has been found desirable 30 to increase the volume of the tank car dome so as to permit of the vaporization occurring when such liquid hydrocarbons are transported without an undesirable rise of pressure in the tank or excessive loss 35 by escape through the safety valves. With this object in view my invention consists of a tank car dome extending longitudinally of the tank a sufficient distance to obtain the desired volume.

40 In Fig. 1 of the drawings, A designates the car tank attached by straps B, or in any desired manner, to the car frame C, of any usual or desired construction, carried by suitable trucks D. 2 designates my im-

proved tank dome, which consists of a 45 middle section 3, substantially semi-cylindrical in shape and of any desired length, and end sections 4 of a general spherical shape. The end sections may be shaped 50 separately from the middle section and joined thereto by riveting or welding or, for the smaller sizes, the entire dome may be shaped from a single plate at one operation. Placing the dome with its longitudinal axis 55 parallel to the longitudinal axes of the tank

and car frame permits of the dome being extended in the direction of the length of the car so as to obtain the requisite volume for use with the largest tanks without exceeding the permissible car dimensions. 60

The tank and the dome are joined as at 5, in any suitable manner, as by riveting or welding. Provision is made, as shown in the middle section 3 in the drawings, for the dome head opening by means of a flanged collar 6 secured to the tank dome sheet in any suitable manner and in which the cover 7 is screwed. Safety valves 8 are screwed into flanged collars 9 attached to the tank dome sheet. Openings, as 10 and 11, are 65 provided in the tank sheets to permit of entry to the tank and escape of vapor to the dome.

What I claim is:

1. The combination in a tank car, of a tank and a dome for said tank having its 75 longitudinal axis extending lengthwise of the car and having its greatest transverse dimension less than that of said tank.

2. The combination in a tank car, of a tank and a dome for said tank comprising 80 a section of substantially semi-cylindrical shape extending lengthwise of the car and having a radius less than that of said tank.

3. A tank car dome comprising a middle 85 dome section having its longitudinal axis parallel to the longitudinal axis of the tank and its greatest transverse dimension less than that of the tank and end dome sections closing the ends of said middle section.

4. A tank car dome comprising a semi-cylindrical middle dome section extending lengthwise of the tank and having its greatest transverse dimension less than that of the tank and curved end dome sections closing the ends of said middle section. 90

5. A tank car dome comprising a middle section provided with manhole and safety valve openings and end sections closing the ends of said middle section. 95

6. A tank car dome comprising integral 100 middle and end sections extending lengthwise of the tank.

7. An integral tank car dome comprising curved middle and end sections.

8. A tank car having a frame, a tank car 105 carried by said frame and a dome on said tank having its longitudinal axis parallel to the center line of said frame and its greatest transverse dimension less than that of said tank. 110

9. A tank car having a frame, a tank carried by said frame and a semi-cylindrical dome for said tank having a radius less than that of said tank, said frame, tank and dome having their longitudinal axes parallel.
10. A tank car having a frame, a tank carried by said frame and a dome for said tank comprising a semi-cylindrical middle section and curved end sections extending lengthwise of the frame.
11. An integral tank car dome comprising a middle and end sections pressed from a single sheet of metal.
12. An integral tank car dome comprising curved middle and end sections formed from a single sheet of metal.
13. An integral tank car dome comprising a semi-cylindrical middle section and

spherical end sections pressed from a single sheet of metal.

14. In a tank car, a tank and a dome for said tank having its longitudinal axis extending lengthwise of the tank and having a diameter different from that of the tank.

15. In a tank car, a tank and a dome for said tank having a semi-cylindrical middle section of a diameter different from that of said tank and curved end sections engaging said middle section and said tank.

In witness whereof I have hereunto set my hand in the presence of two witnesses.

JOHN J. McBRIDE.

Witnesses:

OSCAR HOCHBERG,
T. H. GIBBS.
